UNITED STATES PATENT OFFICE

105,175

DESIGN FOR A DRESS ENSEMBLE

Jack Kirschner, New York, N. Y.

Application May 28, 1937, Serial No. 69,593

Term of patent 3½ years

To all whom it may concern:

Be it known that I, Jack Kirschner, a citizen of the United States of America, residing in Manhattan, county of New York, and State of New York, have invented a new, original, and ornamental Design for a Dress Ensemble, of which the following is a specification, reference being had to the accompanying drawing, forming part hereof, wherein,

The rear portion of the dress unit is conventional.

I claim:

The ornamental design for a dress ensemble, substantially as shown and described.

JACK KIRSCHNER.
